UNITED STATES PATENT OFFICE.

HARRY B. CONKLIN, OF INDIANAPOLIS, INDIANA, ASSIGNOR TO E. C. ATKINS & COMPANY, OF INDIANAPOLIS, INDIANA, A CORPORATION OF INDIANA.

FEEDER ROLL.

Application filed May 9, 1923. Serial No. 637,847.

To all whom it may concern:

Be it known that I, HARRY B. CONKLIN, a citizen of the United States, residing at Indianapolis, in the county of Marion and State of Indiana, have invented a new and useful Feeder Roll, of which the following is a specification.

My invention relates to improvements in feed rolls and particularly feed rolls for edging machines, and it is one of the objects of my invention to provide a feed roll having means whereby, as the lumber-engaging teeth on the periphery of the roll become worn the periphery of the roll may be resurfaced at a minimum cost.

For the purpose of disclosing my invention I have illustrated one embodiment thereof in which—

Fig. 1 is a longitudinal sectional view of a feed roll embodying my invention, and

Fig. 2 is a sectional view taken on the line 2—2 of Fig. 1.

In the structure illustrated, I provide a shaft 1 which, intermediate of its ends, has an enlarged portion 2. At one end of this enlarged portion there is provided an annular flange 3; the opposite end of the enlarged portion has a diameter less than the diameter of the flange 3 and is screw threaded to receive a collar 4 internally screw threaded, which collar when in place, forms at the opposite end, a flange corresponding in diameter to the flange 3.

The enlarged portion 2 of the shaft has an external diameter of such dimension as to have a sliding fit with a tubular facing 5. Each end of this facing is internally enlarged to fit over the flange 3 and the collar 4, and the facing is longitudinally grooved to receive a key 9 which likewise fits in a longitudinally extending groove in the enlarged portion 2. This tubular facing is preferably formed of ordinary commercial double strength piping and has its outer surface longitudinally serrated as at 6. The assembly of the structure is obvious. When the serrated surface of the tubular facing 5 becomes so worn as to be inefficient in operation, the collar 4 is removed by unscrewing and the tubular facing may be removed.

A new tubular facing is then slipped into

position until its enlarged end fits over the annular flange 3. The collar is again screwed in position until the internal annular shoulders 7 and 8 are clamped between the annular flange 3 and the collar 4. The key 9 locks the facing against rotation relatively to the shaft and the structure thus provides a cheap feed roll for edging machines and the like, the periphery of which may be removed from time to time.

I claim as my invention:

1. A feed roller comprising a shaft, a feed roller thereon having at one end an integrally formed annular flange and having its opposite end screw threaded, a longitudinally serrated relatively thin walled tube sleeved over said roller and provided at each end with internal annular shoulders, one of which is arranged to engage the flange of the feed roller, and an internally threaded collar screwed upon the threaded end of the feed roller and forming a removable annular flange arranged to engage the opposite shoulder of the tube to maintain said tube against longitudinal displacement on the roller, and a key for keying said tube on the roller.

2. A feed roller comprising a shaft having integrally formed thereon an enlarged roller portion, said roller portion having at one end an integral annular flange and being screw threaded at its opposite end, a longitudinally serrated relatively thin walled tubular facing for said roller sleeved over said roller endwise and having at its opposite ends internal annular shoulders one of said shoulders being arranged to abut against the flange on the feed roller and spaced a sufficient distance from the end of the tube to permit the tube to enclose said flange, a collar screw threaded on the opposite end of said roller into engagement with one of said shoulders, being likewise spaced from the end of the tube to permit the tube to overhang the collar, and a key for keying the tubular facing to the roller.

In witness whereof I, HARRY B. CONKLIN, have hereunto set my hand at Indianapolis, Indiana.

HARRY B. CONKLIN.
